[57] CLAIM

The ornamental design for a tie-down for use with truck bedliners, as shown and described.

DESCRIPTION

FIG. 1 is an isometric view of the tie-down for use with truck bedliners of the instant invention in the open position;

FIG. 2 is a side elevational view thereof;

FIG. 3 is an end elevational view thereof with the opposite end being a mirror image thereof;

FIG. 4 is a top plan view thereof;

FIG. 5 is a sectional view taken along line 5—5 of FIG. 2;

FIG. 6 is a bottom plan view thereof; and,

FIG. 7 is a sectional view taken along line 7—7 of FIG. 2.

FIG. 1

FIG. 2

FIG. 3

FIG. 4

FIG. 6

FIG. 5

FIG. 7
